UNITED STATES PATENT OFFICE.

WILLIAM A. E. HENRICI, OF CHELSEA, MASSACHUSETTS.

BOSOM-STRETCHER FOR SHIRT-IRONING MACHINES.

SPECIFICATION forming part of Letters Patent No. 568,850, dated October 6, 1896.

[Application filed June 16, 1896. Serial No. 595,765. (No model.)

To all whom it may concern:

Be it known that I, WILLIAM A. E. HENRICI, of Chelsea, county of Suffolk, and State of Massachusetts, have invented an Improvement in 5 Bosom-Stretchers for Shirt-Ironing Machines, of which the following description, in connection with the accompanying drawings, is a specification, like letters on the drawings representing like parts.

10 This invention has for its object the production of a readily - operated device for stretching the bosom and holding firmly the neckband of a shirt upon the work-support of an ironing-machine while the shirt-bosom 15 is being ironed, and it is particularly adapted for use with outing or other shirts having attached collars.

When such a shirt is to be ironed, it is laid upon a suitable support over which an iron 20 may be moved by the operator, the lower end or skirts of the shirt being clamped in any suitable manner.

In order to keep the bosom smooth and taut while being ironed, it must be stretched 25 and held at the neck end, but without interfering with the operator in manipulating the iron, and the retaining device must also be easily put into operative or inoperative position.

30 Figure 1, in front elevation, represents a bosom - ironing machine with my bosom-stretcher and neckband - retainer applied thereto. Fig. 2 is a top or plan view, enlarged, of the bosom-stretcher detached; and 35 Fig. 3 is an outer end view thereof in operative position.

In Fig. 1 I have shown my present invention as applied to a bosom-ironing machine substantially such as is shown in United 40 States Patent No. 556,820, granted to me March 24, 1896, with the yoke-clamp omitted, and the frame A, its top A', the work-support E, the swinging frame C, to which the iron I is attached, the skirt-clamping arm g, and 45 its operating-handle g^x may be and are all as shown in the patent referred to, to which reference may be had.

As shown in Fig. 1, a stand a is rigidly secured to the under side of the work-support 50 E by suitable means, as bolts 2, the stand having a hollow boss a' to receive therein the vertically-movable depending shank b of

the stretcher-support, held in adjusted position by a set-screw 3. Such vertical adjustment is desirable to keep the neckband-holder 55 to the desired height when in operative position, the said support being beyond the neckband of the shirt S (see dotted lines, Fig. 1) and in the central line of the bosom thereof. 60

The upper end of the shank b is bifurcated to form a yoke b', which sustains journals b², herein shown as screw-threaded, for a rocker c, provided with suitable bearings for the journals, whereby the rocker can be tipped 65 on a horizontal axis. The rocker c has an upturned ear c', slotted parallel to its axis, to receive therein a lever d, having a cam portion d', the slot c^x intersecting a squared or polygonal opening at right angles thereto 70 through the rocker.

One of the arms, as b³, of the yoke b' is upwardly extended and recessed or grooved in its inner face at b⁴ in the path of the cam d' when the latter is in operative position, 75 Figs. 2 and 3 and full lines, Fig. 1, to thus lock the rocker from movement.

The band-holder proper consists of a curved, preferably metal, plate f, adapted to be inserted within the neckband or collar of the shirt and rest against the back part, as shown in Fig. 1, the plate f being secured to a curved seat f' on the end of a supporting-arm f², shown as square in cross-section, and entering the longitudinal opening in the rocker c. 80 85

When the handle d is turned down, as shown in Figs. 2 and 3, the cam d' not only locks the rocker from movement, as described, but the periphery of the cam bears upon the top of the arm f² and clamps it 90 firmly, preventing its movement longitudinally in the rocker, so that the band-holder f is clamped in desired position, holding the shirt at the neck end with the bosom stretched and ready to be ironed. 95

In operation the attendant lays a shirt upon the work - support, clamps the skirts, the holder f being unclamped and in dotted-line position, Fig. 1. The attendant moves the holder down into the neckband or collar, drawing its supporting-arm f² forward for the purpose, after which the holder is moved outwardly with one hand, stretching the shirt-bosom, the arm f² sliding outwardly in 100

the rocker *c*. When the bosom is taut, the handle *d* is moved into locking position, clamping the arm and locking the rocker, so that the holder *f* is held immovable, as in 5 full lines, Fig. 1. To release the shirt, the handle *d* is turned up, unlocking the rocker and unclamping the holder-arm, the weight 10 of the outer portion of the arm *f*² usually being sufficient to lift the holder *f* up into dotted-line position, as shown in Fig. 1. The plate *f* is made quite deep from its upper to its lower edge, as shown, and the seat *f'* is secured to its upper portion, so as to leave a considerable space beneath the arm *f*² in 15 which the iron can be moved, if necessary.

As shown in Fig. 1, the lower edge of the holder *f* does not rest on the shirt, as it is only necessary for the holder to bear against the inside of the neckband or collar at its 20 back.

A lug 5 on one side of the handle *d*, Fig. 2, is adapted to bear against a projection 6 on the slotted ear *c'* of the rocker when the latter is unlocked, to limit the movement of 25 the handle in that direction.

By my invention the ironing of cutting and similar shirt bosoms is greatly facilitated, as the bosom is maintained stretched and smooth while the attendant has both hands free to 30 manipulate the iron.

Having described my invention, what I claim as new, and desire to secure by Letters Patent, is—

1. In a bosom-stretching device for shirt-35 ironing machines, a holder to engage the neckband or collar of the shirt, a rigidly-at-

tached arm, a pivotally-mounted support for and in which said arm is longitudinally movable, and means to lock the arm and retain the holder in fixed position, substantially as 40 described.

2. In a device of the class described, a vertically-adjustable pivotally-mounted rocker, an arm longitudinally movable in the rocker, a holder on said arm, to engage the neckband or collar of a shirt, and means to simultaneously lock the rocker from pivotal movement and to clamp the arm therein, substantially as described.

3. In a device of the class described, a yoke 50 having a depending shank, means to hold the latter in vertically-adjusted position, a rocker pivoted in the yoke, a holder having an arm longitudinally movable in the rocker, and means carried by the rocker to clamp the arm 55 therein, substantially as described.

4. In a device of the class described, a yoke having a grooved side, a rocker pivotally mounted in said yoke, a holder, an arm secured thereto and longitudinally movable in 60 the rocker, and a locking member pivotally mounted on the rocker, to engage the grooved side of the yoke and prevent tipping of the rocker and also to clamp the holder-arm in the latter, substantially as described.

In testimony whereof I have signed my name to this specification in the presence of two subscribing witnesses.

WILLIAM A. E. HENRICI.
